H. SWARTZ

COAL GAS CARBURETOR

Original Filed Feb. 3, 1921

INVENTOR

HENRY SWARTZ

BY
John C. Baige
ATTORNEY

UNITED STATES PATENT OFFICE.

HENRY SWARTZ, OF PHILADELPHIA, PENNSYLVANIA.

COAL-GAS CARBURETOR.

Original application filed February 3, 1921, Serial No. 442,218. Divided and this application filed December 17, 1921. Serial No. 523,152.

To all whom it may concern:

Be it known that I, HENRY SWARTZ, a citizen of the United States, residing at Philadelphia, in the county of Philadelphia and State of Pennsylvania, have invented a certain new and useful Improvement in Coal-Gas Carburetors, whereof the following is a specification, reference being had to the accompanying drawing.

10 My invention relates to devices designed to mix atmospheric air with the gaseous primary products of combustion from a coal fire to facilitate the complete combustion of such products and consequent economy of fuel.

15 The form of my invention hereinafter described is adapted as an accessory attachment for an ordinary house heating furnace. However, it is to be understood that it may be employed in conjunction with any type of furnace.

20 As hereinafter described; my improved device includes a tubular air conduit having means to rigidly secure it in an opening extending through the door or wall of a furnace; said conduit carrying, at its inner end, a mixing chamber with air inlets and outlets and having, at its outer end, means adapted to afford a permanent air inlet port 25 of predetermined size and valvular means whereby additional air inlet ports may be opened and closed.

25 This is a division of my application Serial No. 442,218 filed February 3, 1921 for Letters Patent of the United States; the claims in that application being limited to the specific construction and arrangement of the parts of the device extending within the furnace chamber, whereas, the claims in this case 30 are limited to the specific details of construction and arrangement of the air inlet valvular means aforesaid.

35 My invention includes the various novel features of construction and arrangement hereinafter more definitely specified.

40 In said drawing; Fig. I is a plan view of a carburetor embodying my invention.

Fig. II is an outer end elevation of said carburetor.

45 Fig. III is a vertical sectional view of said carburetor taken on the line III, III in Fig. I.

50 Fig. IV is a transverse vertical sectional

view of the mixing chamber shown in Figs. I and III.

55 In said figures; 1 is a tubular air conduit (conveniently formed of a piece of one-quarter inch gas pipe) fitted through the opening 2 in the door or wall 3 of a furnace inclosure, and carrying, at its inner end, the mixing chamber 5, which is rigidly connected with said conduit 1 by the screw thread 6 and jam nut 7. Said chamber 5 is conveniently formed of a single casting of iron alloyed with silicon and manganese in such proportions as to resist oxidation. Said chamber 5 overhangs the fire 8 as indicated in Fig. III, so as to come within the primary gaseous products of combustion 9 arising from said fire. Said chamber 5 has at its bottom a series of nozzles 10 which as shown in Fig. IV have respective cylindrical vents 11 outwardly flared at their outer ends. Said chamber 5 also has a series of vents 14 at its inner edge and a series of vents 15 extending obliquely upward with respect to said vents 11 and 14. I also find it convenient to provide said chamber 5 with the baffle plate or rib 17 extending transversely in opposition to the inner end of the air inlet conduit 1 so as to distribute the incoming air throughout said chamber 5.

60 It is to be understood that the heat of the fire 8 causes circulation of air through said vents 11, 14 and 15, inducing the flow of air inwardly through said conduit 1. I prefer to provide said conduit with the inlet port 19, (conveniently formed by drilling said conduit 1) so as to draw back into the furnace any unconsumed gaseous products 65 from said fire 8 which otherwise might tend to escape at the crevices around the door 3, and return the same through the vents aforesaid. However, I provide for a continuous supply of fresh air from the outer atmosphere, as follows:

70 I provide the outer end of said conduit 1 with the valve casing 21 which is engaged therewith by the screw thread 22; said conduit 1 and casing 21 being rigidly connected with said door or wall 3 by the jam nut 23. Said casing 21 is conveniently formed of cast metal having the cross bar 25 with the central screw bearing 26 in coaxial relation with said conduit 1, to receive the screw 27 as a pivot for the rotary cap valve 75

- 28 which is jammed in said bearing so tightly as not to be accidentally displaced from its normal position shown in Fig. III. Said valve 28 is provided with a permanent air ⁷⁰
 5 inlet port 30, of such size as is predetermined to be best suited for the type of furnace in connection with which the carburetor is used; said port being simply a hole drilled through said pivot screw 27.
- 10 However, I also prefer to provide said valve plate 28 with auxiliary ports 32, as shown in Fig. II, which are closed when said valve is in the position indicated in the drawing but which may be partially or ⁷⁵
 15 entirely opened by turning said valve upon its pivot screw 27, and the lugs 34 are provided to conveniently effect such rotation manually. It may be observed that said ports 32 are of such size that they may be ⁸⁰
 20 used to check the fire 8 by a supply of air in excess of that required to effect complete combustion of said primary gaseous products 9.
- I find it convenient to limit the rotary ⁸⁵
 25 movement of said valve 28 by casting the rib 33 upon its inner face, in such position that the opposite ends of said rib encounter said cross bar at the respectively opposite limits of its range of movement.
- 30 However, it is to be understood that I do not desire to limit myself to the precise details of construction and arrangement therein set forth, as it is obvious that various ⁹⁰
 35 modifications may be made therein without departing from the essential features of my invention, as defined in the appended claims.
- I claim:
1. In a coal gas carburetor; the combination with a tubular air conduit having an ⁹⁵
 40 external screw thread at each end thereof, and an aperture intermediate of its ends, adapted to communicate with the interior of a furnace inclosure; of means arranged to rigidly connect said conduit with an opening ¹⁰⁰
 45 in a furnace inclosure including a jam nut; a mixing chamber at the inner end of said conduit of larger cross sectional area than said conduit; a valve casing having a ¹⁰⁵
 50 screw thread connecting it with the outer end of said conduit, and having a cross bar with an axial screw bearing in coaxial relation with said conduit; a rotary valve having an axial bearing in coaxial relation with said cross bar bearing; a pivot extending ¹¹⁰
 55 in said bearings and having a head exterior to said valve, adapted to retain the latter in cooperative relation with said casing; means arranged to continually admit a predetermined air supply, including a port extending through said pivot from the outer atmosphere into said valve casing; said valve ¹¹⁵
 60 having an auxiliary port adapted to be closed by said cross bar, in one position of rotation with respect to said valve casing and to be opened more or less in accordance with the position of rotation of said valve.
2. In a coal gas carburetor; the combination with a tubular air conduit; of means arranged to rigidly connect said conduit with an opening in a furnace inclosure; a valve casing having means connecting it with the outer end of said conduit, and having a cross bar; a rotary valve having an ¹²⁰
 65 axial pivotal connection with said cross bar; means arranged to continually admit a pre-

determined air supply, including a port extending through said axial pivotal connection from the outer atmosphere into said valve casing; said valve having an auxiliary port adapted to be closed by said cross bar, in one position of rotation with respect to said valve casing and to be opened more or less in accordance with the position of rotation of said valve.

- 10 5. In a coal gas carburetor; the combination with a tubular air conduit; of means arranged to detachably connect said conduit with an opening in a furnace inclosure; a valve casing having means connecting it with the outer end of said conduit; a rotary valve having an axial bearing in coaxial relation

with said casing; and means arranged to continually admit a predetermined air supply, including a port extending through said axial bearing from the outer atmosphere into said valve casing; said valve having an auxiliary port adapted to be opened more or less in accordance with the position of rotation of said valve.

In testimony whereof, I have hereunto signed my name at Philadelphia, Pennsylvania, this fourteenth day of December, 1921.

HENRY SWARTZ.
